UNITED STATES PATENT OFFICE.

JOHN T. HAWKINS, OF TAUNTON, MASSACHUSETTS.

CYLINDER PRINTING-MACHINE.

SPECIFICATION forming part of Letters Patent No. 343,027, dated June 1, 1886.

Application filed December 26, 1883. Serial No. 115,603. (No model.)

To all whom it may concern:

Be it known that I, JOHN T. HAWKINS, of Taunton, in the county of Bristol and State of Massachusetts, have invented a new and useful Improvement in Cylinder Printing-Machines, which invention or improvement is fully set forth and illustrated in the following specification and accompanying drawings.

The object of this invention is, first, to adapt the method of delivering the sheet (shown in Patent No. 286,814, granted to me October 16, 1883) to a cylinder-press in which the reciprocating type-bed is actuated by a crank motion and the cylinder geared directly to the bed, the cylinder running in both directions as actuated by the type-bed; second, to provide means for easily raising and lowering the impression-cylinder alternately, as required, so as to make the impression on the printing-stroke and clear the type on the non-printing stroke of the bed, and by the same motion to carry the impression-cylinder away from contact with the delivery-wheels during the non-delivery of the sheet; third, to provide means for easily tripping the impression-cylinder so that it may remain away from contact with the type or form, when desired, during both the forward and backward strokes of the bed; fourth, to so place the bearings of the impression-cylinder as to bring them more nearly over the impression-surface of the cylinder, and to dispense with a shaft fixed in the said cylinder; fifth, to provide a cheap method of journaling the cylinder which will permit of easy adjustment of the impression and allow of the raising and lowering of the cylinder without resorting to sliding arms or rods in which to journal said cylinder, or weights to counterbalance its weight, and to so construct this mechanism as to permit of all the work therefor being done by simple boring and turning only.

In the accompanying drawings, Figure 1 is a side elevation, partly in section, with the larger part of one of the side frames removed, of a cylinder printing-press embodying the invention. Fig. 2 is a rear end elevation of the same, partly in section, with several parts omitted for the sake of clearness. Fig. 3 is a front elevation of part of the impression-cylinder, with a part of the side frame in section, showing the means for adjusting the impres-

sion. Fig. 4 is a side elevation of the same. Fig. 5 is a rear elevation showing part of the impression-cylinder with a portion of the side frame, all in section, further illustrating the means for raising and lowering the cylinder and adjusting the impression. Fig. 6 is a horizontal vertical section, and Fig. 7 a transverse section, both enlarged, of the apparatus constituting the sheet delivery.

The letter A indicates the main frames of the machine; A', a bed-piece to which the frames A are secured.

B indicates the type-bed, and B' the ink-plate.

The letters B² indicate rollers running upon studs in the frames A carrying the type-bed B.

R indicates a rack secured to the bed-piece A', and R' a rack secured to the under side of the type-bed B.

R² indicates a rolling pinion engaging the racks R and R'.

R⁴ indicates a connecting-rod bifurcated at 75 the end, articulated to the shaft of the pinion R², and connecting at the other end to a crank-pin, R⁵, secured within a crank-gear, R⁶.

R⁷ indicates a pinion carried on a shaft, R⁸, journaled in the frames A, to which power is 80 applied in any suitable way.

The letters R⁹ indicate two racks on the top side of the bed B, engaging corresponding gears, R¹⁰, on the ends of the cylinder C.

All the parts described to this point illustrate the movement of the bed and cylinder in the same manner as shown in Patents Nos. 257,576, 257,578, 257,579, 257,580, and 257,581, granted to me May 9, 1882, the cylinder running in both directions, as actuated by the 90 crank R⁸ through the connecting-rod R⁴, pinion R⁷, racks R and R', and racks R⁹.

C indicates the impression-cylinder, and C' a rock-shaft journaled in eccentric bushes C² in the frames A. The rock-shaft C' has its journals running in the eccentric bushes C² turned eccentrically to that portion of the shaft passing through the cylinder C, and the cylinder C is provided with bearings at its ends turning freely upon the rock-shaft C'. On each of the frames A are cast two lugs, A², and upon each of the eccentric bushes C² is cast a single lug, A³. In each of the lugs A² is tapped a set-screw, A⁴, whose ends engage the single

lug A³. By the proper adjustment of the bushes C² by the set-screws A⁴ the pressure of the cylinder upon the form may be adjusted to a nicety and there maintained. Upon one 5 end of rock-shaft C' is secured an arm, a, to which is articulated a connecting-rod, a', whose lower end is in turn articulated to an arm, a'', which is secured to a short rock-shaft, a³, journaled in the frames A. On the inner end 10 of rock-shaft a³ is secured an arm, a⁴, carrying on its end a pin or roller, a⁵.

The letter a⁶ indicates a connecting-rod having on one end a hook, a⁷. The right-hand side or jaw of the hook a⁷, as seen in Fig. 1, 15 is carried downward to a considerably greater length than is necessary to engage the pin or roller a⁵, and its left-hand side or jaw terminates in an inclined plane, a⁸, the hook at this side being only sufficiently deep to engage the 20 pin or roller a⁵ properly. The other end of connecting-rod a⁶ is articulated to a lever, a⁹, fulcrumed upon a stud, a¹⁰, secured to a bracket, a¹¹, extending upward from the base-piece A'. The lever a⁹ carries a roller, a¹², 25 engaging a grooved cam, a¹³. On a short rock-shaft, y, journaled in the frames A on the inside of frames A, is secured an arm, y'. On the free end of the arm y' is a roller, y², upon which the free end of the connecting-rod a⁶ 30 may run. Outside of frame A, as shown in dotted lines, Fig. 1, and in full lines, Fig. 2, is an arm, y³, terminating on its free end with a foot-piece, y⁴. The amount of depression which may be given to the foot-piece y⁴ is limited by a proper stop in the frame A, (not shown,) and is never sufficient to raise the long side of the hook a⁷ above the pin or roller a⁵, while always sufficient to allow the short side of hook a⁷ to be lifted clear of the 35 pin or roller a⁵. The foot-piece y⁴ may be made to pass under a catch on the side frame, A, so that it may be left in the depressed position.

The grooved cam a¹³ is secured in proper position to the shaft R¹¹ carrying the crank-45 gear R⁶.

The parts just described are so proportioned as to cause the rock-shaft C', through the instrumentality of the cam a¹³, and its connecting mechanism, to rotate through an arc of 50 ninety degrees, and the eccentricity given to rock-shaft C' is sufficient to raise the cylinder C a sufficient distance from the form to clear it freely upon the non-printing stroke of the bed. In doing this it also carries the cylinder 55 C to the left, as shown in Fig. 6 by the dotted circle, a similar distance, for purposes herein-after described. This movement of the cylinder C upward and to the left, Fig. 6, is therefore performed at every complete evolution 60 of the machine.

By operating the hook a⁷ and tripping-levers y' y³, the cylinder is left in its elevated position when desired, for by disarticulating the hook a⁷ from the pin or roller a⁵, the cylinder can never be left in contact with the form during the non-printing stroke, no matter at what part of the machine's evolution

the attendant may depress the foot-piece y⁴. Thus, if the foot-piece y⁴ be depressed when the pin or roller a⁵ is in the position shown 70 in Fig. 1, as the long side of hook a⁷ never rises above the pin or roller a⁵, the arm a⁴ will be pushed to the left until the cylinder is brought to the raised position and left in that position so long as the foot-piece y⁴ is kept 75 depressed, as the short side of hook a⁷ will be raised above the pin or roller a⁵, and the same will be true if this operation be performed at any other point than that at which the arm a⁴ is at its extreme left-hand position, Fig. 1. 80 If performed when the arm a⁴ is at its extreme left-hand position, Fig. 1, it will be left there, and if the hook a⁷ is dropped at any other point by the raising of the foot-piece y⁴ by the attendant the inclined plane a⁸ will run up 85 upon the pin or roller a⁵, and cause the hook a⁷ to articulate again with the pin or roller a⁵ at the proper time. The shaft p, journaled in a bracket, p', attached to the base-piece A' in the frame A, is actuated by a drag-crank, p², 90 from the crank-pin R⁵, and carries on its outer end a bevel-wheel, p³. The bevel-wheel p³ meshes with a similar wheel (not shown) on a longitudinal shaft, p⁴, journaled in brackets extending from the frame A. On shaft p⁴ is 95 secured another bevel-wheel, p⁵, engaging a bevel-wheel, p⁶, on a vertical shaft, p⁷. On the upper end of shaft p⁷ is secured a bevel-wheel, p⁸, engaging a bevel-wheel, p⁹, secured on the horizontal shaft p¹⁰, journaled in the 100 frames A. Secured to the shaft p⁴ is a cam, c, engaging a roller, c', carried upon a vertical connecting-rod, c². The connecting-rod c² is bifurcated at its lower end to embrace the shaft p⁴. The upper end of the connecting-rod c² is articulated to a lever-arm, c³. The 105 operation of the cam c through its connecting mechanism raises and lowers the arm c³ at the proper times. The shaft p⁴ is rotated isochronously with the shaft R¹¹, so that the 110 arm c³ is elevated and depressed once for each complete evolution of the machine. The time of rotation of the shaft p¹⁰ is so proportioned that the grippers g g' will meet once for each complete evolution of the machine, and only once. In the machine as shown the shaft p¹⁰ makes three revolutions to each complete evolution of the machine; but this is arbitrary, and may be made in any proportion to suit the other conditions involved. In this construction, then, the shaft 115 p¹⁰ will make three revolutions to each double oscillation of the cylinder C. The respective diameters, and therefore the peripheral velocities, of the wheels W, secured to the shaft p¹⁰, are such that at the time of the meeting of the grippers g g' said grippers shall both be traveling at about the same velocity, or, preferably, the grippers g' slightly the slower of the two sets of said grippers. The peripheral 120 velocity of the cylinder C, carrying the grippers g, will, however, continue slightly the faster until the last end of the sheet is nearly printed, thus bulging the sheet in the mean-

time slightly away from the surface of the cylinder C, as shown at X in dotted lines, Fig. 6; but, by the thereafter retarding action of the crank, the motion of said cylinder becomes 5 slower than that of the uniformly-rotated wheels W until the sheet is again drawn in contact with the cylinder C by the time the printing is completed. After the completion 10 of the printing the cylinder C reverses its rotation, while the wheels W continue on in the original direction, taking the sheet from the cylinder C from this point until completely removed in a direction contrary to that of the motion of said cylinder. By the action of the 15 rock-shaft C', as heretofore explained, at the completion of the printing the cylinder C is not only raised away from the form, but also carried an equal distance to the left, Fig. 6, or away from contact or close proximity to the 20 wheels W, so that upon the passage of the grippers g' the second and third times past the point at which they take the sheet from the grippers g they do not come in contact with the cylinder C, although opened at every 25 revolution of the wheels W by the cam and mechanism shown and described in Patent No. 286,814, above mentioned. This construction renders unnecessary the substitution of a movable cam arranged for opening the grippers g' 30 at every third revolution only of the wheels W. The remaining mechanism for delivering the sheet is fully described in Patent No. 286,814, above mentioned, the air-pump and blast-pipe therein shown being omitted from 35 these drawings. S, Fig. 2, is the cam from which said air-pump is actuated, and the trip-arms t t' are made herein to oscillate on one stud with a stop-joint instead of on two studs, as described in the above-mentioned patent, 40 and the operation of the lever t is downward during the non-printing revolution of cylinder C, instead of upward by the continuously-rotating cylinder, as in the patent above mentioned.

In Patent No. 272,835, granted to me February 45 20, 1883, a type-revolving cylinder is shown in combination with impression-cylinders and eccentric rock-shafts for imparting eccentric motion to said impression-cylinders, said shaft being similar to the rock-shaft C' 50 herein. I do not therefore herein claim said combination; but,

Having thus fully described my said improvements as of my invention, I claim—

1. In a cylinder printing-press, the combination 55 of a reciprocating type-bed provided with a toothed rack, an impression-cylinder, as C, geared to and oscillated by said rack, and a rock-shaft journaled in exterior set bearings and provided with eccentric journals 60 whereon said cylinder is mounted in internal bearings freely turning upon said eccentric journals, whereby the impression-surface of said cylinder is both elevated out of contact with the type-surface on said bed and lowered 65 into such contact without ungearing said cylinder and rack, substantially as and for the purposes set forth.

2. In a printing-press, the combination, with a reciprocating type-bed, of an impression-cylinder, as C, turning freely on an eccentric 70 rock-shaft, as C', and eccentric bushes, as C², for the reception of the journals of said eccentric rock-shaft, whereby said cylinder is adapted to be turned in either direction upon its axis, is eccentrically oscillated, and also adjusted to regulate the impression, substantially 75 as and for the purposes set forth.

3. In a printing-press, an eccentric rock-shaft, as C', carrying an impression-cylinder, as C, freely turning thereon, in combination 80 with mechanism for automatically operating said rock-shaft, as arm a, connecting-rod a', arm a², rock-shaft a³, arm a⁴, carrying pin a⁵, hooked connecting-rod a⁶, arm a⁷, roller a⁸, and cam a⁹, substantially as and for the pur- 85 poses set forth.

4. In a printing-press, mechanism for tripping the impression-cylinder through the oscillation of a rock-shaft, as a¹⁰, consisting of an arm, as a¹¹, secured to said rock-shaft, and carrying a pin or roller, as a¹², and connecting-rod, as a¹³, actuated, substantially as described, by any suitable moving part of the machine, and carrying on its free end an unequal-jawed hook, as a¹⁴, and an inclined plane extending 95 from its shorter jaw, as a¹⁵, and suitable means for disconnecting the shorter jaw of the hook while leaving the longer jaw free to act, as arm y', roller y², rock-shaft y, arm y³, and foot-piece y⁴, substantially as set forth. 100

5. In a cylinder printing-press, in combination with a reciprocating type-bed, as B, an impression-cylinder, as C, oscillated by said bed at a varying velocity, and provided with sheet-grippers, as g, and a receiving cylinder 105 or cylinders, as W, continuously rotated at a uniform velocity, and provided with sheet-grippers, as g', said cylinders being thus actuated by means, substantially as described, whereby provision is made for the respective 110 sets of grippers to coact to transfer the sheets from said oscillating to said receiving cylinder only at the point where said cylinders reach the same angular velocity in their respective rotations, substantially as and for the purposes 115 set forth.

6. In a cylinder printing-press having a reciprocating type-bed and an impression-cylinder provided with internal bearings turning freely upon an eccentric rock-shaft, as C', 120 the combination of said cylinder-shaft and a delivery-cylinder or series of delivery-wheels, as W, so that the eccentricity of said shaft, while lifting the impression-cylinder to clear the form, shall at the same time move it away 125 from actual contact with or out of close contiguity to said delivery-cylinder or series of delivery-wheels, substantially as and for the purposes set forth.
